UNITED STATES PATENT OFFICE.

BERTHA CAROLINA COLE, OF WILLIAMSON, NEW YORK.

MATCH-SCRATCHING DEVICE.

SPECIFICATION forming part of Letters Patent No. 775,296, dated November 22, 1904.

Application filed April 25, 1904. Serial No. 204,731. (No model.)

To all whom it may concern:

Be it known that I, BERTHA CAROLINA COLE, a citizen of the United States, residing at Williamson, in the county of Wayne and State of New York, have invented certain new and useful Improvements in Match-Scratching Devices, of which the following is a specification, such as will enable those skilled in the art to which it appertains to make and use the same.

The object of this invention is to provide a match-scratching device which may be suspended from a wall or other support or held in any desired manner and which is adapted to receive and hold brimstone or other combustible substances which drop from a match when ignited; and with this and other objects in view the invention consists in a device of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a perspective view of my improved match-scratching device; Fig. 2, a central vertical section thereof on the line 2 2 of Fig. 1, and Fig. 3 a plan view thereof.

In the practice of my invention I provide a box or receptacle *a*, which in the construction shown is oblong in form and provided with a front opening *a*² and the top portion of which is provided with a vertically-arranged member *b*, which is hollow and provided with a central vertically-arranged slot or opening *b*² and the back of which is provided with a vertically-arranged scratcher *b*³, which may be formed integrally therewith or formed separately and secured thereto, and the slot or opening *b*² in the form of construction shown communicates with a transverse slot or opening *c* in the top of the box or receptacle *a*.

In the form of construction shown the vertically-arranged member *b* is flat at the back and provided at the top with a hole *b*⁴, whereby the scratcher may be suspended from a nail,

hook, or other support, and in practice the end of a match is inserted through the slot or opening *b*² and moves downwardly, the end thereof pressing on the scratcher *b*³. In this operation the match is ignited, and any brimstone or other combustible substance falling from the match drops into the box or receptacle *a* and may be removed therefrom whenever desired through the opening *a*².

This device may be suspended from a wall or other support, as hereinbefore stated, or it may be set on a mantel or table and held in the hand when used.

The upright member *b* is open at the bottom, and the box or receptacle *a* is provided in the top with an opening *d*, which corresponds with the hole or opening in the upright member *b*, and this permits the brimstone or other substances to fall into the box or receptacle *a*.

I also connect with the device match-holders *e*, and my improved match-scratching device is thus made to serve as a match-box or match-safe, and instead of throwing a burned match on the floor after it has been used it may be cast into the box *a* through the front opening *a*² therein.

Having fully described my invention, what I claim as new, and desire to secure by Letters Patent, is—

A device of the class described, comprising an oblong box having a front longitudinal opening, and a hollow upright member mounted centrally on said box and communicating therewith through a transverse opening in the top thereof which also communicates with the front longitudinal opening in the box, said hollow upright member being provided with a front vertical slot which opens downwardly and at the back of which is a match-scratcher, substantially as shown and described.

In testimony that I claim the foregoing as my invention I have signed my name, in presence of the subscribing witnesses, this 21st day of April, 1904.

BERTHA CAROLINA COLE.
